BRAKE HANGER

Frederic Schaefer, Pittsburgh, Pa.

Application April 10, 1944, Serial No. 530,255

5 Claims. (Cl. 188—209)

This invention relates to railway car brake hangers, and more particularly to hangers having horizontal cross arms that are elongated in transverse section so as to interlock with the members to which they are connected.

The inner surfaces of brake hanger cross arms normally engage seats provided in hanger bracket wear plates and brake heads. To limit the movement of each hanger arm off its seat, the adjoining seat-forming member is provided with a confining surface on the side of the arm opposite the seat and spaced vertically from the adjacent end of the hanger. In the case of old-style hangers with round cross arms, the clearance between the cross arms and adjacent confining surfaces was a quarter of an inch. That clearance was so great that it permitted excessive vibration of the hanger relative to its seats, thereby causing undue wear.

To decrease that clearance and to lock the cross arms in the members to which they are connected, a brake hanger has been developed having its cross arms elongated in transverse section lengthwise of the hanger. This elongation takes up most of the clearance between the ends of the hanger and the adjacent confining surfaces. Also, it requires the hanger to be disposed substantially horizontally before its upper arm, for example, can be slipped through the narrow entrance to the seating area of the wear plate. When the hanger is then swung down into vertical position, the cross arm is interlocked with the wear plate and can not be removed from its seating area. The same type of interlock is also provided between the lower cross arm and the brake head. This hanger is a great improvement over the old round arm type, but due to the advantageous elimination of most of the clearance between the hanger ends and adjacent confining surfaces, tilting of the hanger in its own plane is quite restricted. Tilting is desirable in order to let the brake beam swing lengthwise so that the brake shoes can follow the wheels if they move axially toward one side or the other of the car truck. Ordinarily, the limited tilting of these hangers is sufficient, but if the journals are allowed to approach the limits of permissible wear the axle may move lengthwise so far relative to the truck side frames that the brake beam can not follow it because the beam is restrained by the hangers. The result is that the brake shoe at one end of the beam rides part way off the outer edge of the adjoining wheel while the shoe at the other end of the beam rides up on the flange of the other wheel. Obviously, both of these conditions are undesirable.

It is an object of this invention to provide a brake hanger, of the type normally having slight clearance at its ends, which can tilt in its own plane to a greater degree than hangers of this type known heretofore; which has a widened outer surface at the central part of each end; and which can be readily formed without altering the basic design of the hanger.

In accordance with this invention a brake hanger is provided which, when it is mounted in a hanger bracket and a brake head, has at the middle of its ends the usual slight clearance that normally exists between the ends of an interlocking type brake hanger and the adjacent confining surfaces of the bracket and brake head. If, however, the hanger is U-shape with a pin through its upper end, it has a cross arm only at its lower end, so it is only with the lower end of such a hanger that we need be concerned here. The outer surface of each cross arm, instead of being longitudinally straight and parallel to its inner surface, is convex lengthwise. This produces increasing clearance outwardly toward both ends of the arm between the outer surface of the arm and the adjacent confining surface. As a result, the cross arm can be tilted relative to its seat much farther than would be possible if the clearance were uniformly small from end to end of the cross arm. Moreover, this increased tilting is sufficient to permit the brake beam to move lengthwise with the wheels even though their journals may have worn about as much as is permitted.

Preferably, the outer surface of the cross arm has a central area that is substantially straight lengthwise and parallel lengthwise to its inner surface. It is this central area that normally is closest the confining surface of the member in which the arm is seated. From this central area the outer surface of the cross arm is inclined inwardly toward the opposite ends of the arm. Also, the central area preferably is made wider than the immediately adjoining areas of the outer surface by thickening the outer central portion of the cross arm.

The preferred embodiment of the invention is illustrated in the accompanying drawing in which Fig. 1 is a fragmentary view showing a brake head supported by my improved brake hanger from a hanger bracket; Fig. 2 is an end view of the hanger; Fig. 3 is a side view of the hanger at its upper end; and Figs. 4, 5, and 6 are transverse sections taken on the lines IV—IV, V—V, and VI—VI, respectively, of Fig. 1.

Referring to Fig. 1 of the drawing, a conven-

tional brake hanger bracket 1 is shown projecting inwardly from the upper part of the side frame 2 of a railway car truck. Mounted in the jaw of this bracket is a U-shape wear plate 3 of well-known form having a transversely concave hanger seat 4 extending across its inner end. The inner portion of the wear plate curves upwardly behind the seat, and then the plate extends forward to provide a bearing surface or confining surface 5 above the seat. The forward portions of the bracket and wear plate are provided with vertically aligned holes through which a cotter pin 6 or other fastener extends for holding the plate in the bracket.

Resting on wear plate seat 4 is the upper cross arm of an integral loop brake hanger of the interlocking type well known in this art. The round and vertical side arms 8 of this hanger are connected at their ends by upper and lower cross arms 9 which are elongated vertically in transverse section, as shown in Figs. 4, 5, and 6. Preferably, these arms are tapered or pear shape in transverse section with the upper arm being tapered upwardly and the lower arm tapered downwardly.

The lower cross arm of this hanger extends through a recess in the central portion of a brake head 12 attached to one end of a brake beam 13. The upper surface 14 of this recess is concave transversely and forms a seat for the upper or inner surface of the lower cross arm. The lower surface 15 of the seating recess forms a confining surface that limits upward movement of the brake head relative to the hanger. From what has been disclosed thus far, it will be seen that the brake head and beam are supported by the brake hanger in the customary manner.

It is a feature of this invention that, although there is as little as about a sixteenth of an inch clearance between the ends of the hanger and the adjacent confining surfaces 5 and 15, this hanger can tilt in its own plane an amount sufficient to permit the brake shoes (not shown), which are carried by the brake heads mounted on beam 13, to follow the wheels throughout the extent of their axial movement. Accordingly, the transversely convex outer surfaces of the cross arms, i. e., the upper surface of the upper arm and the lower surface of the lower arm, are curved outwardly lengthwise of the cross arms. The center of each of these convex surfaces preferably is spaced about a sixteenth of an inch from the adjacent confining surface so that vertical vibration of the hanger is restrained in the same way as heretofore. Nevertheless, by limiting this small clearance to the central part of the cross arm, the latter can tilt lengthwise relative to its seat to a greater degree than if the same clearance existed along the full length of the arm.

It will be understood, as illustrated in broken lines in Fig. 1, that whenever the brake beam is urged to move lengthwise in either direction, it will cause each of its supporting brake hangers to tilt sideways so that one end of its upper cross arm will lift off seat 4 while the opposite end of its lower cross arm will leave seat 14. At the same time, the brake beam necessarily will be lifted a short distance by the hangers, but brake head seat 14 will remain horizontal and parallel to wear plate seat 4.

Preferably, the part of each cross arm closest to the adjacent confining surface consists of a small area 17 that is substantially straight length-

wise and is normally horizontal, which makes it substantially parallel lengthwise to the straight inner surface of the same arm. With a standard hanger which is about six inches across, this central area may be about an inch long for best results. The rest of the cross arm's outer surface, at the ends of this horizontal central area, is inclined inwardly from area 17 to the opposite ends of the arms, either in a straight or a gently curved line. The inclination of these areas 18 is such that, when the cross arm is tilted on its seat, neither one will engage the adjacent confining surface before the adjoining end of the central area does so. Thus, tilting is limited only by engagement of either end of the straight central area with the adjacent confining surface, and that allows the maximum degree of tilting for the length of central area 17. Moreover, for the same minimum clearance, this maximum is considerably more than it would be if the entire outer surface of the arm were parallel to its inner surface and to the adjacent confining surface.

Due to areas 18 of the outer surface of each cross arm being inclined away from the adjacent confining surface of the supporting or supported member, only the restricted outer central area 17 will engage the confining surface while the hanger is being shaken up and down or placed under compression while it is hanging straight down from the bracket. To decrease the resulting wear thus concentrated on this restricted area, it is preferred to increase its size, without affecting the tilting feature, by making it wider and thereby compensating to some extent for the surface area lost by inclining the areas 18. The central areas 17 may be widened conveniently by transversely thickening the central outer portions of the cross arms, as shown in the drawing. The central area, as shown in Fig. 2, therefore becomes considerably wider than the adjoining ends of inclined areas 18. Metal for the thickened central portion of each cross arm can be obtained during the forging operation by gathering it into the forging dies from the arm's end portions which, due to inclined surfaces 18, do not require so much metal as heretofore.

A brake hanger made in accordance with this invention does not need to be replaced, when journal wear becomes appreciable, by an old-style round arm hanger which will tilt more than the usual interlocking hanger, but which will also introduce the disadvantage of excessive lost motion with its resultant vibration and wear.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

65 I claim:

1. A brake hanger having a cross arm provided with an inner surface adapted to engage a seat with slight clearance normally existing between the central area of the arm's outer surface and an adjacent confining surface, said arm being tapered outwardly in transverse section toward said outer surface with the central portion of the arm tapered less sharply than the adjoining portions, said inner surface and said central area being substantially parallel lengthwise, and

said outer surface being inclined inwardly from said central area toward the opposite ends of said arm, whereby to permit increased longitudinal tilting of the cross arm relative to its seat.

2. A brake hanger having a one-piece cross arm tapered outwardly in transverse section, the inner surface of the arm being curved transversely to permit transverse rocking of the arm, the central portion of said arm being tapered less than the adjoining portions to thereby widen the central area of the arm's outermost surface, and said outermost surface being inclined inwardly from said central area toward the opposite ends of said arm.

3. An integral brake hanger having upper and lower cross arms connected at their ends by vertical legs, each of said arms being pear shape in transverse section with the central area of its outer surface substantially parallel lengthwise to the axis of the arm, said outer surface being inclined inwardly from said central area toward the opposite ends of the arm, and said central area being materially wider than the areas of said surface immediately adjoining it.

4. The combination with a wear plate and a brake head each provided with a transverse brake hanger seat opposite a confining surface, of a brake hanger having upper and lower cross arms with inner surface engaging said seats for suspending the head from the wear plate, there be-

ing a slight clearance normally between the central area of each arm's outer surface and the adjacent confining surface, each of said central areas being wider than the immediately adjoining outer surface areas to thereby provide enlarged central bearing areas, and said outer surfaces being inclined inwardly from said central areas toward the opposite ends of said arms, whereby to permit sidewise movement of the brake head relative to said wear plate.

5. The combination with a wear plate and a brake head each provided with a transverse brake hanger seat opposite a bearing surface, of a brake hanger having upper and lower cross arms interlocking with said wear plate and brake head with the inner surfaces of said arms engaging said seats, the upper arm being tapered upwardly and the lower arm being tapered downwardly with their central portions tapered less sharply than the adjoining portions to provide relatively wide central outer surface areas, there being a slight clearance normally between said central areas and the adjacent confining surfaces of the wear plate and brake head, and the outer surfaces of the arms being inclined inwardly from said central areas toward the opposite ends of said arms, whereby the cross arms can tilt on their seats to permit sidewise movement of the brake head relative to said wear plate.
